Office Action issued Apr. 5, 2013, in Korean Patent Application No. 30-2012-0030661 (with English language translation).

Primary Examiner — Susan Bennett Hattan*Assistant Examiner* — Janice Hallmark(74) *Attorney, Agent, or Firm* — Oblon, Spivak, McClelland, Maier & Neustadt, L.L.P.**CLAIM**

The ornamental design for a hand-held aerosol generator, as shown and described.

DESCRIPTION

FIG. 1 is a perspective view of a hand-held aerosol generator showing my new design as viewed from the left side of the page;

FIG. 2 is a side elevational view of one side thereof;

FIG. 3 is a top plan view thereof;

FIG. 4 is a side elevational view of the opposite side thereof;

FIG. 5 is a bottom plan view thereof;

FIG. 6 is a front plan view thereof; and,

FIG. 7 is a rear plan view thereof.

1 Claim, 4 Drawing Sheets See application file for complete search history.
